CLAIM

The ornamental design for a heel protector, as shown and described.

DESCRIPTION

FIG. 1 is a top front perspective view of a first embodiment of a heel protector showing my new design; FIG. 2 is a front elevation view of FIG. 1; FIG. 3 is rear elevation view of FIG. 1; FIG. 4 is a right side elevation view of FIG. 1, the left side elevation view being a mirror image thereof; FIG. 5 is a top plan view of FIG. 1; FIG. 6 is a bottom plan view of FIG. 1; FIG. 7 is another top front perspective view of FIG. 1, shown in a used condition with a shoe shown in broken lines; FIG. 8 is a top front perspective view of a second embodiment of a heel protector showing my new design; FIG. 9 is a front elevation view of FIG. 8; FIG. 10 is rear elevation view of FIG. 8; FIG. 11 is a right side elevation view of FIG. 8, the left side elevation view being a mirror image thereof; FIG. 12 is a top plan view of FIG. 8; FIG. 13 is a bottom plan view of FIG. 8; and, FIG. 14 is another top front perspective view of FIG. 8, shown in a used condition with a shoe shown in broken lines. The stippling shading in FIGS. 8-14 represent a contrast in textured surface. The broken lines of the shoe in FIGS. 7 and 14 depict environmental subject matter and form no part of the claimed design, while all other broken lines depict portions of the heel protector that form no part of the claimed design.
